(57) **CLAIM**

The ornamental design for the tongs, as shown and described.

DESCRIPTION

FIG. 1 is a perspective view of the tongs, showing our new design;

FIG. 2 is a top plan view thereof, wherein a bottom plan view is a mirror image thereof;

FIG. 3 is a left side elevation view thereof, wherein a right side elevation view is a mirror image thereof;

FIG. 4 is a front elevation view thereof; and,

FIG. 5 is a rear elevation view thereof.

The broken lines in the figures illustrate portions of the tongs that form no part of the claimed design.
